James P. Morris

United States Patent Office.

JAMES P. MORRIS, OF BLOOMINGTON, ILLINOIS.

Letters Patent No. 67,064, dated July 23, 1867.

IMPROVED CAR-COUPLING.

The Schedule referred to in these Letters Patent and making part of the same.

TO ALL WHOM IT MAY CONCERN:

Be it known that I, JAMES P. MORRIS, of Bloomington, in the county of McLean, and State of Illinois, have invented a new and useful Improved Safety Car-Coupling; and I do hereby declare that the following is a full, clear, and exact description thereof, which will enable others skilled in the art to make and use the same, reference being had to the accompanying drawings, forming part of this specification, in which—

Figure 1 is a side view of my improved car-coupling showing it in a working position.

Figure 2 is a horizontal section of the same, taken through the line $z-z$, fig. 1, showing the inside of the jaws and position of the spring E, the recess C for the more secure holding of the link-block G, and the spring holders D D at the sides.

Figure 3 is a vertical section of the coupling showing the position of the link and link-block, and more effectually the ledges B B.

Figure 4 is a separate view of the link in connection with the link-block.

Figure 5 is a detached view of the side holders or catches, in combination with the spring.

Figure 6 is a view of the bolt or fastening-pin used in connecting the cars.

My invention has for its object to furnish an improved coupling to insure greater safety to trains running upon railroads, by constructing the "bumper" or coupling in such a manner that while affording secure hitching as long as the cars remain in proper position upon the rails, yet upon any one being thrown from the track it will readily detach itself from the train without dragging other cars with it, whether the car thus thrown off be in the front, middle, or rear of the train. And it consists, first, in the "bumper" being constructed nearly in the usual manner, the exceptions being that the jaws for the admission of the link are open at the sides, and have flanges or ledges for the secure holding of the link-block, and further furnished with catches or holders at the sides of the bumper working on pins, and kept in place by a spring so as to effectually prevent the link from escaping until it is turned to a certain angle; second, the combination, with the above-described "bumper," of a link furnished at one of its ends with a link-block working freely therein, for the purpose of securely coupling the cars when in proper position, and yet affording the means of ready uncoupling, should the necessity occur, as hereinafter more fully described.

A, fig. 1, represents the car-coupling in its proper working position, with link and link-block in place as holding the cars together, the other end of the link to be held in place by the bolt or pinion in the usual manner. This coupling may be made of cast iron, wrought iron, or other equivalent material, by the usual well-known methods of constructing couplings by skilled artisans, with a recess, C, as shown in fig. 2, for the more secure holding of the link-block in a central position, the ledges or flanges b b, and side catches D D in connection with the spring E. The dotted lines I K show the position of the link and catch in the act of separation, while the vertical section, fig. 3, explains more fully the construction of the ledges b b, which hold the link securely in its place by means of the link-block G; a better view of the same being found in fig. 4. Said block being a solid mass of cast or wrought iron of a conical shape, with a groove in its edges to admit of free play of the link upward or downward, the block being held in place at the end of the link by a spur or projection shown at L, fig. 4. The holders or side catches D D are fully explained by the drawing, fig. 5, in connection with the spring E, which is a simple bar-spring attached to the catches by loops, and bent into place in the coupling, as shown at n, fig. 2, and the catches secured by pins at o o to the coupling.

Having thus described my invention, I claim as new, and desire to secure by Letters Patent—

1. A "bumper" constructed after the manner as shown herein, with ledges b b, recess C, catches D D, spring E, substantially as and for the purpose specified.

2. The combination of the bumper, link, link-block, and the several parts of each with each other, substantially as described and for the purposes specified.

JAMES P. MORRIS.
